BEVERAGE DISPENSING AND DISPLAY DEVICE

Filed March 2, 1929

UNITED STATES PATENT OFFICE

HARRY C. SMITH, OF NEW YORK, N. Y., ASSIGNOR TO THE AUTODRINK CORPORATION,
OF NEW YORK, N. Y., A CORPORATION OF DELAWARE

BEVERAGE DISPENSING AND DISPLAY DEVICE

Application filed March 2, 1929. Serial No. 344,027.

This invention relates to beverage dispensing and display devices of the type in which a constant circulation of beverage is adapted to be maintained from a refrigerated storage receptacle through a transparent display container and back to the storage receptacle.

A purpose of the present invention is to provide a device of the type mentioned comprising essentially a storage receptacle, a display container and a circulating line of piping between said receptacle and said container, and to provide for dispensing of the beverage from said circulating line after it leaves the storage receptacle and prior to its entrance into the display container, whereby the dispensed beverage will be at substantially the same temperature as the main body of beverage in the storage receptacle.

Other purposes of the invention are to provide a simple, inexpensive means of enabling a dispensing spigot to be connected with the feed line between the storage receptacle and the display container; to provide a spigot connection which will assure a good flow of beverage from the spigot whenever same is opened; to provide a simple means of illuminating the display container and, in general, to provide a beverage dispensing and display device which is composed of few parts compactly arranged and capable of quick assembly and disassembly to permit expeditious cleaning of the device.

With the foregoing and other purposes in view, the invention consists in the novel features of construction, combination and arrangement of parts as will be hereinafter more fully described, illustrated in the accompanying drawing and defined in the appended claim.

In the accompanying drawing, wherein is illustrated a preferred embodiment of the invention, the figure is a vertical section through a beverage dispensing and display device constructed in accordance with the invention.

Referring to the drawing by numerals, it will be observed that the present beverage dispensing and display device, in accordance with common practice, includes essentially a beverage storage receptacle A, refrigerat-

ing apparatus B for maintaining beverage within receptacle A cool, and a display container C through which beverage from receptacle A is adapted to be constantly circulated.

Container C consists of a hollow, transparent body 10 of any suitable size, shape and design, normally closed at its open top by a removable cover 11 and provided at its bottom with an opening 12 through which extends a tube 13, any suitable sealing means such as gaskets 14 being provided to prevent leakage of beverage from the container body 10, passed tube 13 through opening 12.

Container C is supported upon a base 15 within which is arranged a casting 16 having a pair of separate passages 17 and 18 formed therethrough. This casting is attached to the lower end of tube 13, which latter is in communication with passage 18, while communicating with passage 17 is a pipe 19 which is carried by said casting 15 and projects upwardly through tube 13 any suitable distance into body 10.

Connecting passage 17 with a bottom portion of receptacle A is a pipe 20 in which is interposed a pump 21 adapted to be driven in any suitable manner to take beverage from receptacle A and deliver it through said pipe 20, passage 17 and pipe 19 into the interior of body 10, while connecting passage 18 with a top portion of receptacle A is a pipe 22 through which beverage delivered into body 10 and overflowing tube 13 will be conducted by way of passage 18 back to receptacle A.

In order to cause beverage delivered into body 10 from the upper end of pipe 19 to flow in a pleasing and attractive manner through said body, pipe 19 has mounted thereon a preferably hollow member 23 of any desired shape having a stepped or otherwise irregularly formed outer face over which the beverage is adapted to flow in a cascade-like manner. This member 23 preferably is formed of translucent material and is adapted to be illuminated from the interior thereof to further add to the attractiveness of the display. To this end, I mount in casting 16 a conduit 25 which extends upwardly through tube 13 into the interior of member 23 where it supports an electric lamp 26, and in order to protect

the lamp circuit conductors 27 from the beverage which is circulated through body 10 and tube 13, said conductors are housed within in conduit 25, casting 16 being provided with 5 a third passage 28 through which the conductors 27 are adapted to be led from conduit 25 to a suitable source of current.

In accordance with the purpose of providing for dispensing of the beverage prior to 10 its entrance into body 10, a spigot 30 is connected with passage 17, through an opening 29 in the side of casting 15. Further, the ends of passage 17 are disposed out of axial alignment with one another to provide a baffle 15 wall 31 for changing the direction of flow of beverage from pipe 20 to pipe 19, and opening 29 is located adjacent to said baffle wall whereby, due to back pressure of the beverage 20 at the point where its direction of flow is changed, said beverage will tend to flow with substantially equal pressure through spigot 30 when same is opened as through pipe 19.

Refrigerating apparatus B, which may be 25 of any preferred type, is inclusive of a cooling coil 32 disposed against receptacle A, whereby the beverage therein may be maintained at a desired temperature.

With pump 21 in operation it is apparent 30 that beverage from receptacle A will be delivered through pipe 20, passage 17 and pipe 19 into body 10 and that said beverage will, upon rising in body 10 to the level of the top of tube 13, overflow said tube and gravitate back to receptacle A through passage 18 and pipe 22. Thus the beverage will be maintained thoroughly mixed so long as 35 pump 21 is in operation, and as is further apparent, due to the fact that dispensing spigot 30 is located to take beverage from the feed line prior to its entrance into the body 10, the beverage dispensed will be at substantially the same temperature as the beverage in receptacle A, particularly if pipe 20 is 40 heat insulated as is contemplated.

As will be observed from the drawing, tube 13 has threaded connection with casting 16 and the latter also has threaded connection with pipes 19, 20, 22 and conduit 25 so that 45 the parts of my device are capable of being readily disassembled for cleaning purposes and as readily assembled following cleaning.

From the foregoing description considered 50 in connection with the accompanying drawing it is believed that the construction, operating and advantages of the invention will be clearly understood. It is pointed out, however, that various changes and desirable additions may be made in and to the structure 55 shown within the spirit and scope of the invention as defined in the appended claim.

I claim:

In a beverage dispensing and display device, a beverage display container, a tube 60 extending through the bottom of said contain-

er, a member connected with the lower end of said tube, said member having a pair of 70 passages extending from top to bottom therethrough, one of said passages being in direct communication at its upper end with said tube, a pipe connected with the upper end of the other of said passages extending through said tube into the display container, beverage return and feed pipes connected with the lower ends of said passages, respectively, and a casing surrounding said member and said pipes, said member constituting a nut for clamping said casing rigidly with respect to said container.

In testimony whereof I hereunto affix my 80 signature.

HARRY C. SMITH.
